UNITED STATES PATENT OFFICE.

MORGAN PARKER, OF NEWPORT, RHODE ISLAND.

SURGEON'S KNIFE.

1,100,394.

Specification of Letters Patent. Patented June 16, 1914.

Application filed January 16, 1913. Serial No. 742,403.

To all whom it may concern:

Be it known that I, MORGAN PARKER, a citizen of the United States, and resident of Newport, in the county of Newport and State of Rhode Island, have invented a new and useful Improvement in Surgeons' Knives, of which the following is a specification.

This invention relates to certain new and useful improvements in surgeons' knives, and the object of the invention is to provide a knife of the type set forth which has but two parts, namely, a handle and a blade which is removably attached to the handle, so that the two parts can be readily separated for the purpose of sterilization, thus facilitating the latter operation.

A further object of the invention is to provide simple and improved means whereby the blade may be easily and quickly attached to or removed from the handle.

In the drawings Figure 1 is a plan view of the invention. Fig. 2 is a side elevation, partly broken away and in section. Fig. 3 is a plan view of the removable blade. Fig. 4 is a perspective view of the handle member, and Fig. 5 is a side elevation, the blade being shown in section and in the act of being secured to the handle member.

The handle member 1 may have the hand gripping portion thereof of any desired form or shape, and is formed with a spring arm 2 that is integral therewith. The inner end of the handle member 1 is formed with a socket 3 which aligns with the arm 2 and provides a seat for the inner end of the blade 4. The blade 4 is formed with apertures 5 and 6 located adjacent the respective ends thereof. The spring arm 2 is formed with the inner stud 7 and an outer stud 8, the latter having its portion adjacent the free end of the spring arm 2 undercut at 9, the wall of the aperture 5 being inclined at 10 so as to engage with the undercut portion 9 of said stud 8.

In operation, in attaching the blade to the handle member, the spring arm 2 is bowed as illustrated in Fig. 5, whereupon the inner end of the blade 4 is placed in the socket 3 and the stud 7 is caused to enter the aperture 6 of the blade, after which the stud 8 is placed in the aperture 5, and the spring arm released so as to assume its position in a straight line as depicted in Fig. 2, which will cause the undercut portion 9 of the stud 8 to frictionally bind against the in-

clined wall portion 10 of the aperture 5, in which position of the parts it will be obvious that the blade 4 will be firmly held in position.

By forming the spring arm 2 integral with the handle 1, the number of parts is reduced to two, namely, the handle 1 and the blade 4, which greatly facilitates the sterilizing operation. It will also be apparent that the blade 4 can be easily and quickly applied to or removed from the handle member, since in the latter operation it is merely necessary to flex the arm 2 to the position shown in Fig. 5 whereupon the outer end of the blade may be moved outwardly from engagement with the stud 8, after which the arm 2 is permitted to resume its normal position, at which time the stud 7 can be moved out of the aperture 6 and the blade withdrawn from the socket 3.

Having thus described my invention, I claim as new and desire to secure by Letters Patent;

1. A knife consisting of a handle member formed with an integral spring arm, the inner end of the handle having a socket located adjacent said arm, a stud on the inner end of the arm, a stud on the outer end of the arm formed with an inwardly extending undercut portion, and a blade having an inner aperture to receive the inner stud and also having an outer aperture to receive the outer stud, the outer aperture being formed to provide an inclined wall which engages the undercut portion of the outer stud, the inner end of the blade being received in said socket.

2. A knife including a handle member provided with a spring arm, a blade seating on one side face of the arm, and interengaging means between the blade and arm for holding the blade on the arm by virtue of the spring tension exerted by said arm on said blade, said interengaging means being released by flexure of said arm.

3. A knife consisting of a handle member, a spring arm connected at one end to the handle member, a blade seating on one side face of the arm, means to secure the inner end portion of the blade against movement relative to the handle member, and means on the outer end portion of the arm to engage the blade to secure same to the arm, said means being engageable with and disengageable from the blade by flexing of the arm.

4. A knife consisting of a handle member, a spring disposed to lie parallel with the longitudinal axis of the handle member and connected to the latter, a blade seating on 5 one side face of the spring, the handle member having a socket that receives one end of the blade, and means on the outer end portion of the arm to engage the blade, said 10 means being engageable with and disengagable from the blade when the spring is

flexed in a plane approximately transverse to the longitudinal axis of the spring.

In testimony whereof I have signed my name to this specification in the presence of two subscribing witnesses.

MORGAN PARKER.
